ERNST LIESKE, OF NORTH ARLINGTON, NEW JERSEY, ASSIGNOR OF ONE-HALF TO
FREDERICK W. LAPP AND ONE-HALF TO OTTO C. REITH, BOTH OF NEW YORK, N. Y.

RADIATOR ATTACHMENT.

1,299,970.

Specification of Letters Patent.

Patented Apr. 8, 1919.

Application filed December 5, 1918. Serial No. 265,406.

To all whom it may concern:

Be it known that I, ERNST LIESKE, a citizen of Germany, residing at North Arlington, in the county of Bergen and State of 5 New Jersey, have invented an Improvement in Radiator Attachments, of which the following is a specification.

This invention relates to an attachment for steam radiators, and the object thereof 10 is the provision of an article that can be used in conjunction with steam radiators to moisten the air in the room in which the radiator is situated.

It is well understood that the use of steam 15 radiators for heating purposes is more or less general, and also it is understood that the heat produced by steam radiators is exceedingly dry and more or less detrimental to health. I have found that by the use of a 20 radiator attachment hereinafter described, the air in a room or other place heated by a steam radiator is maintained in such a condition as to contain the necessary or at least an adequate percentage of moisture.

25 In carrying out the invention, the receptacle forming the radiator attachment is made of clay or a composition of the same and other materials, so as to be of a sufficiently porous nature for the purposes specified, and as hereinafter more particularly described, the article being so shaped and constructed as to be attached to a steam radiator, fitting partially between the loops or coils thereof, and also so constructed, that 30 when in use, the water employed in the same will not drip therefrom to the floor.

In the drawing:

Figure 1 is a front elevation of a steam 40 radiator illustrating the use of the present invention.

Fig. 2 is a side elevation on an enlarged scale of my improved radiator attachment.

Fig. 3 is a plan view of the same, and

Fig. 4 is a longitudinal section taken on 45 line 4—4, Fig. 3.

Referring particularly to the drawing, the radiator attachment comprising my present invention consists of a body member indicated at 10 having a convex front wall 11 and 50 concave side walls 12 and 13, so that in plan or cross section, the attachment assumes a general angular form, permitting the concave walls 12 and 13 to fit and extend between the coils or loops of the radiator. 55 The attachment is open-ended as indicated,

the top being open as shown at 14 while the bottom is open as shown at 15. In a suitable position between the top and the bottom, preferably approximately one-third of the distance from the bottom, there is a 60 transverse partition wall 16. The concave side walls are united at an angular portion 17 in which there is a suitable hole 18 adjacent the top of the attachment, so that by the employment of suitable hooks 20, or 65 other supporting and connecting members, the radiator attachment may be fixed in position upon a steam radiator. As indicated in the drawing, the lower end of the hook 20 is passed through the opening 18 while 70 the upper end of the hook is fitted over the connecting bars or rods 21, uniting the upper portion of the loops or coils 22 of the steam radiator so that the attachment is supported from the radiator, as shown in Fig. 1. In 75 the angular portion 17, I may also provide a hole 19 preferably placed immediately below the partition wall 16 for ventilating purposes, that is, so that a current of air may pass through the chamber in the lower 80 portion of the attachment.

The improved radiator attachment hereinbefore described is known in the markets as the "Moistenair" attachment, and is made of clay or a mixture of clay and other suitable materials in such proportions that the article is porous, permitting the water to trickle through the walls of the attachment and to be evaporated by the heat emitted from the radiator, the porosity of the attachment being such of course that under normal operating conditions, only sufficient water will work through the walls of the attachment as will be evaporated by the heat from the radiator. The purpose in placing the 85 partition wall 16 at a distance from the bottom of the attachment is to provide an apron to take up the water which trickles through the porous walls and prevent the same from dripping therefrom to the floor, it having 90 been found in practice that when in use, the lower end of the attachment for approximately an inch or so from the bottom will be entirely dry.

It will be understood that while I have 105 herein shown and described the article made in accordance with my invention as particularly applicable to use in conjunction with steam radiators, it may be used to good advantage in hot-water radiators, gas radia- 110

tors, or in any place with or without radiators, to properly moisten the air in a given place; as for example, houses in exceedingly dry climates. Furthermore, if desirable, a 5 disinfectant or perfume may be added to the water when the same is placed in the receptacle.

I claim as my invention:

- 10 1. A radiator attachment comprising a body member having walls of porous material and a partition dividing the same into compartments, one of which is adapted to receive a liquid with that portion of the walls below the partition forming an apron 15 adapted to absorb the liquid which trickles through from the liquid compartment and from which the liquid is evaporated so that it will not drip therefrom to the floor.
- 20 2. A radiator attachment comprising an open ended body member having walls of porous material and having a convex front wall and concave side walls adapted to fit between the coils of a steam radiator and a transverse partition wall forming a water

compartment and a depending apron adapted to absorb the water which trickles through from the water compartment and from which the water is evaporated so that it will not drip therefrom to the floor. 25

3. A radiator attachment comprising a body member having cylindrical walls of porous material and a partition dividing the same into compartments, one of which is adapted to receive a liquid with that portion of the walls below the partition forming a cylindrical apron adapted to absorb the liquid, which trickles through from the liquid compartment and from which the liquid is evaporated so that it will not drip therefrom to the floor, there being a perforation 35 provided in the cylindrical wall forming part of the apron immediately below the said partition. 40

Signed by me this 25th day of November, 1918.

ERNST LIESKE.

Witness:

RICHARD E. SMITH, Jr.
